UNITED STATES PATENT OFFICE.

HORACE W. KING, OF ANN ARBOR, MICHIGAN.

DEPTH-INDICATING DEVICE.

1,423,118.

Specification of Letters Patent.

Patented July 18, 1922.

Application filed April 1, 1920. Serial No. 370,417.

To all whom it may concern:

Be it known that I, HORACE W. KING, a citizen of the United States of America, residing at Ann Arbor, in the county of Washtenaw and State of Michigan, have invented certain new and useful Improvements in Depth-Indicating Devices, of which the following is a specification, reference being had therein to the accompanying drawings.

10 The invention relates to devices for indicating the depths of liquids and is particularly applicable to motor vehicles for indicating the depth of the liquid fuel in the fuel tank.

15 The invention has for one of its objects the provision of means for drawing air into a chamber within the tank and communicating with the liquid fuel at the full depth to be measured and of means permeable to 20 air and substantially impermeable to the liquid fuel for preventing the liquid fuel from being drawn through the suction pipe which is connected to the fuel tank. Another object of the invention is the provision 25 of a unit detachably mounted upon the tank and comprising the air chamber and means for preventing the liquid fuel from being drawn through the suction pipe. Further objects of the invention reside in the 30 novel arrangements and combinations of parts as more fully hereinafter set forth.

In the drawings:

Figure 1 is a longitudinal sectional view, partly in elevation, of a construction embodying my invention;

Figure 2 is a top plan view of a portion of a tank containing the liquid fuel to be measured and showing the top of that portion of the depth indicating device which is 40 mounted upon the tank.

1 is a tank containing liquid fuel, such as gasoline, and 2 an internal combustion engine intake manifold of a motor vehicle.

3 is an air chamber formed by a tube 4 having a closed upper end and depending vertically from the top of the tank 1, the lower end of this tube being open and terminating adjacent to the bottom of the tank 1. 5 is a tube having its upper end communicating with the air outside the tank 1 and its lower end communicating with the interior of the tube 4 at substantially the same level as this tube communicates with the gasoline in the tank. The tube 5 preferably extends longitudinally within the tube 4. For producing a vacuum in the tank

1 sufficient to draw air through the tube 5 the suction pipe 6 is provided connecting into the intake manifold 2 and into the top of the tank 1. 7 is a suitable pressure gauge 60 such as a U gauge having the legs 8 and 9 which are respectively connected to the pipes 10 and 11 for transferring the pressure of the air in the tube 4 and in the tank 1, respectively.

65 In order to prevent the drawing of gasoline from the tank 1 through the suction pipe 6 and into the intake manifold 2, in the event that the tank is substantially full and some of the gasoline may splash upwardly adjacent to the connection of the suction pipe, the following construction is provided. 12 is a dome upon the top of the tank 1, this dome having the annular shoulder 13. 14 is a diaphragm permeable to air 75 but substantially impermeable to gasoline, this diaphragm extending transversely of the dome 12 and being secured between the annular shoulder 13 and the nut 15 threadedly engaging the interior of the dome and 80 having the passage way 16 therethrough. The suction pipe 6 is detachably connected to the top of this dome as by means of the union 17 securing the pipe to the nipple 18. Suitable fibrous material 19, such as felt, 85 may be provided upon the upper side of the diaphragm 14 for supporting the latter, this material also being adapted to absorb any gasoline which might pass through the diaphragm.

90 In order to readily detach that portion of the depth indicating device mounted on the tank 1 the cover or cap 20 is provided to which the tubes 3 and 4 and the dome 12 are secured, the latter being preferably integral with the cover or cap. The nipples 21 and 22 to which the pressure pipes 10 and 11 are respectively connected by suitable unions are also mounted upon this cover or cap in position to communicate respectively with the interiors of the tube 4 and tank 1. 23 is a securing member having the annular base flange 24 fixedly secured upon the top of the tank 1 and the cylindrical externally threaded flange 25. 26 is a nut 100 threadedly engaging this flange and having at its outer end the inwardly extending flange 27 engaging the outer peripheral surface of the cover or cap 20 and adapted to force this cover or cap toward the end of 110 the cylindrical flange 25. 28 is a suitable packing between the cover or cap and the

outer end of the cylindrical flange 25 for making an air tight joint.

In operation the suction in the intake manifold 2 draws air from the interior of the gasoline tank 1 through the pipe 6, when the engine is running. Due to the partial vacuum in the tank, air is drawn through the inner tube 5, which air enters the outer tube 4 at substantially the level of the point of communication thereof with the gasoline and displaces the gasoline from this outer tube. The pressure of this air counterbalances the hydrostatic head of the gasoline down to the lower end of the outer tube and when transferred to a suitably graduated gage 7 indicates the depth or amount of the gasoline. The diaphragm 14 permits of the passage of air into the pipe 6, but prevents substantially the passage of gasoline thereto. The fibrous material 19 absorbs any small amount of gasoline which might pass through the diaphragm and additionally supports the diaphragm.

What I claim as my invention is:

1. In a depth indicating device for liquids, the combination with a closed tank containing a liquid, of a chamber communicating with the air outside said tank and with the liquid in said tank, a suction pipe connected to said tank for producing a vacuum therein sufficient to draw air into said chamber for displacing the liquid down to the point of communication of said chamber with the liquid, means for preventing the passage of the liquid from said tank through said suction pipe, and a pressure gage in communication with said tank above the level of the liquid therein.

2. In a depth indicating device for liquids, the combination with a closed tank containing a liquid, of a chamber communicating with the air outside said tank and with the liquid in said tank, a suction pipe communicating with said tank for producing a vacuum therein sufficient to draw air into said chamber for displacing the liquid down to the point of communication of said chamber with the liquid, a member in the communication between said suction pipe and tank, said member being permeable to air and substantially impermeable to the liquid, and a pressure gage in communication with said tank above the level of the liquid therein.

3. In a depth indicating device for liquids, the combination with a closed tank containing a liquid, of a chamber communicating with the air outside said tank and with the liquid in said tank, a dome upon said tank, a source of vacuum, a pipe connected to said source of vacuum and said dome, a diaphragm extending across said dome permeable to air and substantially impermeable to the liquid for preventing the liquid being drawn into said source of vacuum, and a

pressure gage in communication with said tank above the level of the liquid therein.

4. In a depth indicating device for liquids, the combination with a closed tank containing a liquid, of a chamber communicating with the air outside said tank and with the liquid in said tank, a dome upon said tank, a source of vacuum, a pipe connected to said source of vacuum and said dome, a diaphragm extending across said dome permeable to air and substantially impermeable to the liquid, fibrous material on the upper side of said diaphragm forming a support therefor and adapted to absorb any liquid passing therethrough, and a pressure gage in communication with said tank above the level of the liquid therein.

5. The combination with a closed tank containing a liquid, of a device for indicating the depth of the liquid in said tank comprising a tube extending into said tank and having an open lower end terminating near the bottom thereof, a cover or cap for closing the upper end of said tube, said cover or cap being removably secured to said tank, a second tube extending longitudinally within said first-mentioned tube and having an open lower end terminating near the bottom of said tank and an open upper end communicating with the air outside said cover or cap, a dome upon said cover or cap, a transversely extending diaphragm clamped in said dome, said diaphragm being permeable to air and substantially impermeable to the liquid, a suction pipe connecting into said dome above said diaphragm and a pressure gauge for indicating the difference in pressures of the air inside said first mentioned tube and inside said tank.

6. The combination with a closed tank, containing a liquid and an intake manifold, of a detachable device for indicating the depth of the liquid in said tank comprising a cover or cap, a nut for detachably securing said cover or cap to the top of said tank, a chamber secured to said cover or cap and communicating with the liquid in said tank at the full depth to be measured, a tube secured to said cover or cap and communicating with the air outside the same and with the interior of said chamber at substantially its point of communication with the liquid, means detachably secured to said cover or cap for indicating the difference of pressures of the air in said air chamber and tank, and a suction pipe detachably communicating with said intake manifold and detachably connected to said cover or cap for effecting sufficient vacuum in said tank to draw air through said tube into said air chamber to displace the liquid therefrom.

In testimony whereof I affix my signature.

HORACE W. KING.
